UNITED STATES PATENT OFFICE.

OTTO F. HEER, OF ONTARIO, CALIFORNIA.

PIPE MOLD.

Application filed February 9, 1922. Serial No. 535,177.

To all whom it may concern:

Be it known that I, OTTO F. HEER, a citizen of the United States, residing at Ontario, in the county of San Bernardino and State of California, have invented new and useful Improvements in Pipe Molds, of which the following is a specification.

My invention relates to pipe molds, and a purpose of my invention is the provision 10 of a pipe mold of that character in which either the casing or core or both are slowly rotated during the tamping operation, my invention consisting in forming the core with a liner which is removable to allow of 15 the substitution of a new liner when the first becomes worn and useless.

It is also a purpose of my invention to provide a pipe mold core which permits and facilitates the forming thereof of true 20 circular contour thereby effecting the forming of a pipe of uniform thickness.

I will describe one form of pipe mold and two forms of cores all embodying my 25 invention and will then point out the novel features thereof in claims.

In the accompanying drawings,

Figure 1 is a view showing in vertical section one form of mold embodying my 30 invention with a portion of the core in elevation.

Fig. 2 is a top plan view of the mold shown in Fig. 1.

Figs. 3 and 4 are transverse sectional views taken on the lines 3—3 and 4—4, respectively, of Fig. 1.

Fig. 5 is a fragmentary sectional view showing the construction of the joints of the core cylinder and liner.

Fig. 6 is a fragmentary sectional view showing a modified means for securing the core to the bell ring.

Similar reference characters refer to similar parts in each of the several views.

Referring specifically to the drawings, my 45 invention, in its present embodiment, comprises a turntable T adapted to be supported for rotational movement by any suitable means such as that shown in my Patent No. 1,330,760, issued February 10, 1920. A pin 15 is threadedly fitted within the table T and arranged axially thereof to form centering means for a bell ring B, the latter being of the contour shown in Fig. 1.

The pipe mold per se comprises a casing 50 K of tubular form and having an outwardly flared lower end to co-operate with the bell

ring in forming the joint portion of the pipe as will be understood. Handles k are fixed at diametrically opposite points to the casing for facilitating the application or 60 removal of the same to the table T. This casing K is adapted to be fixedly secured upon the turntable T by means of clamping bars 16 having upstanding terminal extensions 16^a adapted to contact with the lower 65 end of the casing K and securely hold the same in engagement with the bell ring B. The bars 16 are secured in clamping position by means of screws 17 mounted in the table T and extending through slots formed 70 in the bars, all as clearly shown in Fig. 1.

Within the casing K and supported upon the bell ring B is the core of the mold, such core being designated generally at C and including an inner cylinder 18 and an outer cylinder or liner 19. The inner cylinder 18 is formed by rolling a sheet of metal into cylindrical form and securing the vertical edges thereof by welding as indicated at 20 in Fig. 5. In forming this cylinder, rings 21 are employed which, as clearly 75 shown in Fig. 1, are arranged adjacent the opposite ends of the cylinder and secured therein by means of bolts 22. These rings are formed from angle bars which can be rolled to form a perfect circle so that when inserted into the cylinder and secured thereto they hold the cylinder in true cylindrical formation.

The outer cylinder or liner 19 is arranged 80 in surrounding relation with respect to the inner cylinder and the bolts 22 are utilized for securing the two together, while other bolts 22^a are extended through the cylinders adjacent their split portions for securing 85 the outer cylinder in contiguous relation with respect to the inner cylinder. As clearly shown in Figs. 1 and 5, all outer bolts are provided with countersunk heads so as to provide a smooth surface for the 90 core. As the outer cylinder is held in contiguous relation with the inner cylinder, it will be clear that the outer cylinder also occupies a true cylindrical form so that the core as a unit when in position within the 95 casing K will co-operate with the latter in molding a pipe of uniform internal diameter.

As shown in Figs. 1 and 2, the inner cylinder 18 is provided with a brace bar 23 to 100 which threaded rods 24 are connected, and these rods are adapted to be associated with

suitable elevating means (not shown) for moving the core as a unit into and out of the casing K. For preventing displacement of the core from the bell ring B, a positioning pin 25 is threadedly fitted within the core and axially thereof. This pin is removably fitted within a suitable opening formed in a block 26 secured centrally within the core by bars 27 in the manner clearly shown in Fig. 3.

In operation, the table T continues to rotate by suitable means not shown and such as embodied in my Patent No. 1,330,760, issued February 10, 1920. During such rotation the concrete contained between the core C and the casing K is tamped in the usual manner in effecting a formation of the pipe. Continued use of the mold obviously causes the wearing away of the core C thus necessitating the renewal of the core at frequent intervals. The labor and expense attendant these substitutions is eliminated by the employment of the core C constructed in the manner previously described, as it will be manifest that all wear takes place on the surface of the liner 19, and when this liner becomes unduly worn it can be readily removed from the inner cylinder 18 and a new one substituted.

In Fig. 6 I have shown a modified means for removably associating the core C with the bell ring B. In this embodiment, the end of the cylinder 18 is provided adjacent its lower end with a bar 28 having upturned ends which are secured to the cylinder by bolts 29. This bar 28 carries depending pins 30 which are adapted to engage within the recesses formed in the upper side of the bell ring B, the arrangement of the pins being such that when the bell ring is rotated a corresponding movement is imparted to the core.

Although I have herein shown and described only one form of pipe mold embodying my invention, it is to be understood that various changes and modifications may be made herein without departing from the spirit of the invention and the spirit and scope of the appended claims.

What I claim is:

1. A pipe mold comprising a turntable, a casing sustained on the turntable, a bell ring removably associated with the table, clamping bars adjustable on the turntable and co-operating with the bell ring for clamping the casing on the turntable, and a core sus-

tained on the bell ring and comprising an inner cylinder and an outer cylinder removably associated with the inner cylinder.

2. A pipe mold comprising a turntable, a bell ring sustained on the turntable, a centering pin carried by the turntable and engaging the bell ring for centering the latter on the turntable, a casing surrounding the bell ring, clamping bars adjustable on the turntable and co-operating with the bell ring for fixedly securing the casing to the turntable, a core sustained on the bell ring, a block carried by the core, and a pin on the bell ring and engaging said block for centering the core on the bell ring.

3. In a pipe mold, a core comprising an inner split cylinder, rings within the cylinder for maintaining the latter in true cylindrical formation, an exterior liner received on the cylinder and means extending through the cylinder, liner, and rings for securing the same together.

4. A pipe mold comprising a turntable, a bell ring sustained on the turntable, a centering pin carried by the turntable and engaging the bell ring for centering the latter on the turntable, a casing surrounding the bell ring, means for fixedly securing the casing to the turntable, a core sustained on the bell ring, a block carried by the core, and a pin on the bell ring and engaging said block for centering the core on the bell ring.

5. A pipe mold comprising a turntable, a casing sustained on the turntable, a bell ring removably associated with the table, means adjustable on the turntable and co-operating with the bell ring for clamping the casing on the turntable, and a core sustained on the bell ring and comprising an inner cylinder and an outer cylinder removably associated with the inner cylinder.

6. A pipe mold comprising a turntable, a bell ring sustained on the turntable, a centering member carried by the turntable and engaging the bell ring for centering the latter on the turntable, a casing surrounding the bell ring, means for fixedly securing the casing to the turntable, a core sustained on the bell ring, a member carried by the core, and a member on the bell ring and engaging the core carried member for centering the core on the bell ring.

In testimony whereof I have signed my name to this specification.

OTTO F. HEER.
